UNITED STATES PATENT OFFICE.

HENRY F. DOBBIN, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE INSTRUMENT.

Application filed July 20, 1923. Serial No. 652,755.

To all whom it may concern:

Be it known that I, HENRY F. DOBBIN, a citizen of the United States, residing at New York, in the county of New York, State of 5 New York, have invented certain new and useful Improvements in Telephone Instruments, of which the following is a full, clear, concise, and exact description.

This invention relates to telephone 10 station apparatus, and its object is to provide a simple switching mechanism therefor which will prevent the sending of false impulses and the causing of premature disconnections by incomplete movements of the 15 switchhook in either direction.

In accordance with the features of the invention there is provided a switching mechanism comprising a member operated by the switchhook lever against the action 20 of a restoring spring and operating the contact springs at a predetermined time in the switchhook movement through the medium of a lost motion switching mechanism.

The drawing shows a telephone desk stand 25 embodying the invention.

Fig. 1 is a side view of the desk stand with part of the covering removed to reveal the operating mechanism.

Fig. 2 is a bottom view of this mechanism.

Fig. 3 is a front view of the switchhook and its associated mechanism.

Figs. 4^a, 4^b and 4^c show the respective positions of the switchhook, the contact springs, 35 and the spring operating lever when the switchhook is down; and Figs. 5^a, 5^b and 5^c show the relative positions of these members when the switchhook is raised.

The desk stand comprises a stem 7 resting 40 on a base 8 in which a calling dial 9 may be mounted. A transmitter holding member 11 is set into stem 7 and the end of a switchhook 12 is rotatably attached thereto at 13. A vertical shaft 15 in the stem 7 is held 45 against the shank of the switchhook 12 by a spring 16 attached to a terminal plate 17 set in the base 8. The lower portion of shaft 15 is threaded so that there may be screwed thereon a lost motion device comprising an 50 upper stop member such as nut 19 and a lower stop member such as nut 20. Between these nuts is set a stud 22 whose thickness is somewhat less than the distance between the nuts. Stud 22 is attached to a lever 25 55 pivoted at 26 to an extension 27 of plate 17.

A stud 28 on the opposite end of lever 25 from stud 22 bears against a contact spring 29 which forms a part of a bank 30. A second spring 31 is distanced from spring 29 by a stud 32 and operates therewith. As 60 may be seen by referring to Figs. 4^a and 4^b and 5^a and 5^b, the contacts between the springs are open when the switchhook is down and are closed in order to allow the sending of impulses by the calling dial 9, 65 and the completion of the talking circuit when the switchhook is raised. In order to maintain the lever and the springs in either the position shown in Figs. 4^a and 4^b or in the positions shown in Figs. 5^a and 5^b until 70 positive pressure is brought to bear on the stud 22, a third stud 34 is attached to the lever 25 and bears against a spring 35 attached to terminal plate 17. In this spring are two corrugations 36 and 37 into one of 75 which stud 34 fits when the switchhook is raised and into the other of which the stud fits when the switchhook is down. This arrangement prevents the contacts from being opened or closed by a slight movement of 80 the switchhook to cause false impulses to be sent over to the line circuit. The spring 35 holds stud 34 in lever 25 firmly in place until the movement of the switchhook has caused the shaft 15 to be raised or lowered 85 a distance equal to the distance between stud 22 and the nut farthest therefrom so that positive pressure is brought to bear on stud 22 to move lever 25 and stud 34 to make or break contact between the springs. Figs. 4^a 90 to 5^c inclusive, serve to illustrate the manner in which this mechanism operates.

The threading of the lower end of shaft 15 enables the easy adjustment of the lost motion mechanism so as to properly align 95 stud 34 with the corrugations in spring 35.

The invention claimed is:

1. In a telephone instrument, a switchhook, a reciprocating shaft controlled by said switchhook, a member fixed to said shaft and carrying a pair of operating lugs, a lever disposed between said lugs so as to allow said shaft a certain amount of play in either direction without actuating said lever and thereafter actuating said lever, and contact springs actuated by the movement of said lever.
2. In a telephone instrument, a switchhook, contact springs, a shaft actuated by the switchhook, a lost motion mechanism on the 110

2
shaft, and means controlled by said lost motion mechanism and comprising a stud bearing against a corrugated spring member to cause the actuation of said contact 5 springs by the latter part of the switchhook movement in either direction.

3. In a telephone instrument, a switchhook, contact springs, a shaft actuated by the switchhook, a lost motion mechanism on 10 the shaft, a lever operated by the lost motion mechanism, a stud on the lever to actuate said contact springs, and a second stud on the lever bearing against a corrugated 15 spring member, said shaft, lost motion mechanism, lever, studs and corrugated spring cooperating to actuate said contact springs in response to the latter part of the switchhook movement.

4. In a telephone desk stand, a base, a

switchhook having a limited movement, contact springs on the base, a vertical shaft, a lost motion mechanism adjustably mounted on the shaft, and a lever member operated by the lost motion mechanism, a stud on said lever to operate said contact springs, a 25 flat spring member having two corrugations therein, a second stud on said lever bearing against said spring member and adapted to fit in one or the other of said corrugations, said mechanism being so arranged that the 30 contact springs are actuated only in response to the latter part of the switchhook movement in either direction, and means for adjusting said lost motion mechanism.

In witness whereof, I hereunto subscribe 35 my name this 17th day of July A. D. 1923.

HENRY F. DOBBIN.
